HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 6, 1923. Serial No. 655,927.

My invention relates to railway traffic controlling apparatus, and particularly to apparatus of the type comprising train carried governing mechanism controlled by energy received from the trackway. More particularly, my invention relates to the trackway portion of such apparatus.

I will describe one form of railway traffic controlling apparatus embodying my invention, and will then point out the novel features thereof in claims.

In the accompanying drawings, Figs. 1^a and 1^b when placed end to end in the order named form a diagrammatic view showing one form and arrangement of railway traffic controlling apparatus embodying my invention.

Similar reference characters refer to similar parts in each of the figures.

Referring to the drawings, the reference characters 1 and 1^a designate the track rails of a single track railway over which traffic normally moves in both directions, the portion of track shown in the drawing being provided with two passing sidings F and F^a. For purposes of convenience of description I shall hereinafter term that portion of track which lies between the two passing sidings F and F^a, a "stretch of single track," it being understood that by combining the required number of such stretches with the required number of interposed passing sidings F, F^a, etc., a complete system of any desired length may be constructed. The track rails 1 and 1^a of the stretch shown in the drawings are divided, by means of insulated joints 2 into three consecutive track sections A—B, B—C and C—D, it being understood however that any reasonable number of such sections may occur in a single stretch. The main track parallel with the siding F^a is also provided with a track section D—E.

Traffic from left to right over the stretch of track shown in the drawing is controlled by three roadside signals S⁷, S⁷ and S⁹, which are located at points A, D and E, respectively. In similar fashion traffic from right to left over this track is controlled by three other signals S⁰, S² and S⁸ located at points E, D and A, respectively. In other words, a pair of opposing signals is located at each end of each passing siding.

As shown in the drawings, each of the sig-

nals S⁰, S¹, S², S⁷, S⁸ and S⁹ is a colored light signal, and each is provided with three signal lamps 4, 5 and 6, adapted to project, when energized, a beam of red light, yellow light, or green light, respectively, and thus display a "stop," "caution" or "proceed" indication in accordance with common practice.

Each end of each track section is provided with a source of track circuit current such as the secondary 7 of a track transformer designated by the reference character T with a suitable exponent. Each such transformer secondary is constantly connected with the track rails of its associated section, and the primary 8 of such transformer is at times supplied with alternating current by means which will be described in detail hereinafter. Interposed between one track rail 1 and the secondary winding 7 of each transformer T is an impedance 9, one function of which is to limit the output of the transformer when its terminals are short circuited by the wheels and axles of a passing train.

Each section is provided with two track relays, one located at each end of the section, and each of which relays is designated by the reference character R with a suitable exponent. Each such relay comprises a track winding 15 and a second winding 10 which is constantly supplied with alternating current from a suitable source. For example, referring particularly to relay R⁵, winding 10 is provided with a circuit which passes from the secondary of line transformer H^c through wire 11, winding 10 of relay R⁵, and wires 12, 13 and 14 back to transformer H^c. The primary of line transformer H^c is constantly supplied with alternating current from a generator O over line wires 3 and 3^a. A similar line transformer is located adjacent the juncture of each two track sections and is designated by the reference character H with an exponent corresponding to the location.

Associated with each track relay R is a "line" relay designated by the reference character W with the same exponent as that which is applied to the corresponding track relay. Referring particularly to line relay W³, this relay is provided with a circuit which passes from the secondary of line transformer H^c through wires 11 and 16,

front contact 17 of relay W^5 , wires 18 and 19, front contact 20 of track relay R^4 , wire 21, back contact 22 of a "stick" relay K^6 , wire 23, front contact 24 of relay R^3 , wire 25, winding of relay W^3 , and wires 26, 27, 28, 29 and 14 back to transformer H^c . It is plain that this circuit is closed only when relays W^5 , R^4 and R^3 are energized and auxiliary relay K^6 is de-energized. The circuit just traced is provided with a branch which passes from wire 11, through wire 30, front contact 31 of auxiliary relay K^5 and wire 32 to wire 19. It follows that when relay K^5 is energized the closing of its front contact 31 removes the relay W^5 from the control of relay W^3 . The control of relay W^4 is exactly similar to that of relay W^3 . Relay W^5 is controlled by track relays R^5 and R^2 for section C—D, and relay W^6 is controlled by track relays R' and R^6 for section A—B, there being no line relay contacts in the circuits for these relays, and consequently no stick relays associated with such circuits.

Relays W^8 , W' , W^2 , W^1 , W^0 , and W^9 are of the polarized three position type and are each provided with two windings 33 and 34, one of which 33 is constantly connected with a source of alternating current. Referring particularly to relay W^2 , winding 33 of this relay is provided with a circuit which passes from transformer H^D , through wires 39 and 38, winding 33 of relay W^2 , and wires 37, 36 and 35 back to transformer H^D . The relay is arranged to be responsive to reversals of the relative polarity of the current supplied to winding 34 which is provided with a circuit passing from the secondary of an auxiliary transformer M^c whose primary is constantly supplied with alternating current over wires 14 and 11 from transformer H^c . The circuit for winding 34 is from the secondary of transformer M^c through wire 40, front contact 41 of relay W^4 , wire 42, front contact 43 of relay W^4 , wire 44, back contact 45 of auxiliary relay K^4 , wire 46, front contact 47 of track relay R^5 , wire 48, front contact 49 of track relay R^2 , wire 50, winding 34 of relay W^2 , wires 37, 36, 51 and 52, front contact 53 of relay W^4 and wire 54 back to transformer M^c . This circuit is closed only when relays R^2 , R^5 and W^2 are energized and relay K^4 is de-energized under which conditions the polarity of the current supplied to relay W^2 is what I shall term normal relative polarity, and the contact fingers on relay W^2 are swung to the right. When relay W^4 is de-energized, however, as by a train moving from right to left in section B—C, relay K^4 , as will appear hereinafter, is energized and the circuit for winding 34 of relay W^2 then passes from transformer M^c , through wire 40, back contact 53 of relay W^4 , wires 52, 51, 36 and 37, winding 34 of relay W^2 , wire 50, front contact 49 of

track relay R^2 , wire 48, front contact 47 of relay R^5 , wire 46, front contact 45 of relay K^4 , wires 55 and 56, back contact 41 of relay W^4 and wire 54 back to transformer M^c . This circuit is closed only when relays R^2 , R^5 and K^4 are energized and relay W^4 is de-energized, under which conditions relay W^2 is supplied with current of what I shall term reverse relative polarity and the contact fingers on this relay will be swung toward the left. Line relay W' located at point A and line relay W^9 located at point E are controlled by circuits similar to those just traced for line relay W^2 .

Associated with each of the line relays W' , W^7 , W^9 , W^0 , W^2 and W^8 is a repeater relay designated by the reference character G with an exponent corresponding to the location. Each of the repeater relays G is controlled by its associated line relay as follows: Referring for example to repeater relay G^2 located at point D, this relay is provided with a circuit which passes from transformer L^P , whose primary is constantly supplied with alternating current from transformer H^D , through wire 57, normal or reverse contact 58 of relay W^2 , winding of relay G^2 , wires 60 and 68, back contact 61 of track relay R^2 , and wires 62 and 63 back to transformer L^P . This circuit is closed only when relay R^2 is de-energized but it will be noticed that back contact 67 of track relay R^2 is connected in multiple with back contact 61 of track relay R^2 and that the circuit will therefore be closed by de-energization of relay R^2 . Each of the remaining repeater relays G is provided with a circuit similar to that just traced for relay G^2 . In addition, one terminal of each of the relays G^2 , G^7 , G^0 , and G^9 is connected to a common wire 65. Similarly, relays G' and G^8 are connected by means of wire 65^a with two relays at the left hand end of siding F and not shown in the drawing. The result of such connection is that relays G^2 , G^7 , G^0 and G^9 are normally deenergized but that when a train enters section C—D, D—E, or the section to the right of E, these relays will be immediately energized, provided the associated relays W are energized. The operation of the repeater relays G associated with siding F is similar in all respects to that described for the relays associated with siding F^a.

Relay W^7 is controlled as follows: When relay G^0 is energized current of one relative polarity is supplied to relay W^7 over a circuit which passes from secondary of transformer M^B , through wire 80, front contact 79 of relay G^0 , wire 78, front contact 77 of track relay R^9 , wire 76, front contact 75 of track relay R^0 , wire 74, back contact 73 of relay K^0 , wire 72, front contact 71 of track relay R^7 , wire 70, winding 34 of relay W^7 , wires 63 and 83, front contact 81 of relay G^0 ,

and wire 82 back to secondary of transformer M^e . When relay G^o is de-energized current of the other relative polarity is supplied to relay W^7 over a circuit passing from transformer M^e , through wire 80, back contact 81 of relay G^o , wires 83 and 63, through winding 34 of relay W^7 as before to wire 78, back contact 79 of relay G^o , and wire 82 back to transformer M^e . It is therefore clear that, assuming relay K^o to be de-energized and relay R^o , R^o , R^7 to be energized, relay W^7 is energized in one direction or the other depending upon the condition of energization of relay G^o . Line relays W^o and W^s are provided with circuits similar in all respects to those just traced for line relay W^7 .

The auxiliary or stick relay K^4 associated with track relay R^4 is provided with a pick-up circuit which passes from transformer H^c through wires 11 and 84, back contact 85 of relay W^s , wire 86, back contact 87 of track relay R^5 , wire 88, back contact 89 of track relay R^4 , wire 90, front contact 91 of relay W^4 , wire 92, winding of relay K^4 , and wires 93, 94, and 14 back to transformer H^c . The stick relay K^4 will be energized therefore as a train, moving from right to left, enters section B-C at point C. The energizing of this relay closes a retaining or stick circuit which passes from transformer H^c through wires 11 and 95, back contact 93 of relay R^4 , wire 97, front contact 98 of relay K^4 , wire 99, winding of relay K^4 , and thence to wire 93 and back to transformer H^c as before. This retaining circuit is closed only when relay K^4 is energized and relay R^4 is de-energized, and serves to maintain K^4 in its energized condition as long as any part of section B-C is occupied by a train. Stick relays K^o , K^s and K^b are controlled over circuits similar to those just described for relay K^4 .

Auxiliary relay K^o is provided with a pick-up circuit which passes from transformer H^e , through wires 95 and 96, back contact 97 of track relay R^o , wires 98 and 99, front contact 100 of repeater relay G^o , wire 101, winding of relay K^o , and wires 102, 103 and 104 back to transformer H^e . This relay is also provided with a retaining or stick circuit which commences at wire 98 and leads through wire 107, front contact 106 of relay K^o , and wire 105, back to the winding of relay K^o . It follows that the relay is normally de-energized, but is closed by the entrance into section D-E of a train moving from right to left, and remains closed as long as the train occupies such section. A stick relay K^s is controlled by circuits similar in all respects to these just traced for relay K^o .

Relay P^4 serves as a repeater for relay K^s and is controlled over a circuit which commences at transformer H^e , and leads

through wires 108 and 109, front contact 110 of relay K^s , wire 111, back contact 24 of track relay R^s , wire 23, back contact 22 of relay K^s , wire 21, back contact 20 of relay R^4 , wire 112, winding of relay P^4 , and wires 113, 94, 20, 14 and 28, back to transformer H^e . It follows that if relays R^s , R^4 and K^s are de-energized and relay K^s is energized, relay P^4 will close. Similar repeater relays P^s , P^o , P^7 and P^o are controlled over analogous circuits.

As shown in the drawing one end of each section is provided with a source of track circuit current which is normally connected with the rails of the section. Referring particularly to section B-C, transformer T^s has its secondary 7 constantly connected with the rails adjacent the left hand end of this section and its primary winding 8 is provided with a circuit which passes from transformer H^e through wires 108 and 114, back contact 115 of relay K^s , wire 116, primary winding 8 of transformer T^s , and wires 27 and 28, back to transformer H^e . It is evident therefore that track circuit current is supplied to section B-C from transformer T^s only when relay K^s is de-energized. The track transformers T^s , T^o , T^b and T^o are controlled in exactly the same manner as track transformer T^s . Referring again to section B-C a second track transformer T^4 is located at the right hand end of this section and is provided with a circuit which passes from transformer H^e through wires 11 and 117, front contact 118 of relay P^4 , wire 119, primary winding 8 of track transformer T^4 , and wires 94 and 14 back to transformer H^e . Since relay P^4 is energized only when relay K^s is energized, it follows that track circuit current is supplied to section B-C by transformer T^4 only when relay K^s is energized, and that at such time transformer T^s is not supplied with current. Transformers T^s , T^o , T^b and T^o are controlled over circuits similar to the one described for transformer T^s . The track winding 15 of each track relay R^s , R^o , R^b , R^s and R^o is constantly connected with the rails adjacent one end of its associated section. Referring particularly to section B-C, an impedance 117 is interposed between one rail 1 of the section and winding 15 of the relay R^s but means are provided for at times shunting this impedance. Thus a path is provided which passes from one side of impedance 117, through wire 119, front contact 120 of relay K^s and wire 118 back to the other side impedance 117. The purpose of this impedance is to limit the current through the relay when the track transformer at the same end of the section, as T^s is energized. The shunt path just traced is carried over a front contact on relay K^s and we have just found that when relay K^s is energized, track transformer T^s is de-en-

110

112

113

115

116

ergized and track transformer T^4 is energized; therefore the impedance 117 is shunted only when the track circuit is being fed from the opposite end of the section, in which case the current leakage through the section reduces the voltage at the relay R^3 to such value that it can safely be applied to the relay without series impedance. The remaining end of each section is provided with 10 a track relay which is at times entirely disconnected from the track rails. Thus the winding 15 of track relay R^4 is included in a circuit which passes from one rail 1 of the section B—C, through wire 119, winding 15 of track relay R^4 , wire 120, back contact 121, of relay P^4 and wire 122 back to track rail 1^a of section B—C. It is clear that the energization of relay P^4 will completely disconnect relay R^4 from section B—C 20 and that this connection will not be re-established till relay P^4 again becomes de-energized. Circuits are provided for relays R' , R^2 , R^7 and R^9 similar to that just described for controlling relay R^4 .

25 Each of the signals S is controlled by the associated relays W and G as follows: Referring particularly to signal S^2 the stop or red lamp 4 of this signal is provided with a circuit which passes from the secondary of a 30 lighting transformer J^P (whose primary is constantly supplied with alternating current from transformer H^P), through wire 123, back contact 125 of relay G^2 , wire 126, lamp 4 of signal S^2 , and wire 127 back to transformer J^P . This circuit is closed only when relay G^2 is de-energized, which is the normal condition of the apparatus corresponding to the unoccupied condition of track, circuit D^E and also the track circuit to the 35 right of E and in which case lamp 4 is lighted so that signal S^2 displays a stop indication. The caution circuit for signal S^2 passes from transformer J^P through wire 123, front contact 125 of relay G^2 , wire 128, reverse contact 129 of relay W^2 , wire 130, lamp 5 of signal S^2 , and wire 127 back to transformer J^P . This circuit is closed only 40 when relay G^2 is energized and relay W^2 is energized by current of reverse relative polarity, under which conditions lamp 5 is lighted and signal S^2 displays a caution indication. The proceed circuit for this signal passes from transformer J^P through wire 123, front contact 125 of relay G^2 , wire 128, 45 normal contact 129 of relay W^2 , wire 131, lamp 6 of signal S^2 and wire 127 back to transformer J^P . This circuit is closed only when relay G^2 is energized and relay W^2 is energized by current of normal relative polarity under which conditions lamp 6 is lighted and signal S^2 displays a proceed indication.

50 Means are also provided for each section for supplying to the rails in parallel a current which I shall hereafter term a local cur-

rent. For this purpose I connect an impedance 132 across the rails adjacent the left hand end of each section, a similar impedance 133 adjacent the right hand end of each section, and two similar impedances 134 and 135 at intermediate points in each section.

Traffic moving from right to left through section B—C is controlled by local current supplied to the rails by a double secondary local transformer N^B whose primary is constantly supplied with alternating current from transformer H^P over wires 28 and 108. A local circuit for this section passes from secondary 136 of transformer N^B through wire 138, front contact 139 of relay W^6 , wires 140 and 141 to impedance 132 of section B—C, thence through the rails of the section to impedance 133, then through wire 142, back contact 143 of relay P^4 , wire 144, back contact 145 of relay K^3 , wire 146, front contact 147 of relay W^6 , and wire 148, back to transformer N^B . This circuit is closed only when relays K^3 and P^4 are de-energized and relay W^6 is energized, under which conditions the rails of section B—C are supplied with alternating local current of what I shall term normal relative polarity. If, however, section A—B is occupied by a train, relay W^6 is de-energized and the local circuit then passes from secondary 136 of local transformer N^B , through wire 138, back contact 139 of relay W^6 , wire 146, back contact 145 of relay K^3 , wire 144, back contact 143 of relay P^4 , wire 142, impedance 133 in section B—C, through rails of the section to impedance 134, thence by wire 180, front contact 181 of relay K^6 , wire 150 back contact 147 of relay W^6 and wire 148, back to secondary 136 of transformer N^B . This circuit is closed only when relays K^3 , P^4 and W^6 are all de-energized and relay K^6 is energized under which conditions the rails of section B—C are supplied with local current of what I shall term reverse relative polarity between impedances 133 and 134, but with no local current between impedances 132 and 134.

Traffic moving from right to left through section C—D is supplied with local current over circuits similar to those just traced in connection with section B—C.

Traffic from left to right through section A—B is controlled by local circuits similar to those just traced for governing traffic from right to left through section B—C.

Traffic from left to right through section C—D is controlled by a local circuit which passes from secondary 137 of local transformer N^D through wire 124, front contact 151 of relay G^7 , wire 152, normal contact 153 of relay W^7 , wires 154, 155 and 156, impedance 133 in section C—D, through the rails of the section to impedance 132, thence through wire 157, front contact 158 of relay K^5 , wire 159, front contact 160, of relay P^2 , 130

wire 161, normal contact 162 of relay W^7 , wire 163, front contact 164 of relay G^7 , and wire 165 back to winding 137 of local transformer N^D . This circuit is closed only when 5 relay W^7 is energized in the normal direction and relays K^5 , P^2 and G^7 are all energized, under which condition local current of normal relative polarity is supplied to the rails of section C—D between impedance 132 10 and 133. When relay W^7 is energized by current of reverse relative polarity the reversal of contacts 153 and 162 connects wire 155 to wire 163 and wire 161 to wire 152, thus reversing the relative polarity of the 15 local current supplied to section C—D. If relay W^7 is de-energized due to traffic conditions in advance such as the presence of a train in section D—E or the section to the right of E, relay G^7 will also be de-energized 20 and the local circuit for this section then starts with secondary 137 and leads through wire 124, back contact 151 of relay G^7 , wires 166 and 161, front contact 160 of relay P^2 , wire 159, front contact 158 of relay K^5 , wire 25 157, impedance 132 in section C—D, thence through the rails of the section to impedance 135, then by wire 167, back contact 164 of relay G^7 and wire 165, back to secondary 137 of local transformer N^D . This circuit is 30 closed only when relays K^5 and P^2 are energized and relay G^7 is de-energized under which condition the rails of section C—D are supplied with local current of reverse relative polarity between impedances 132 35 and 135, but with no local current from impedance 135 to impedance 133.

Traffic moving from right to left through section A—B and the section to the right of E is governed by local circuits similar to 40 those just described for traffic from left to right through section C—D.

The local circuits for section D—E and the section to the left of A are identical with those already traced for section B—C, with 45 the exception that the pole changing or reversing of the relative polarity of the local current is accomplished here by means of a relay G whereas in section B—C this operation is controlled by the line relay W .

50 Before explaining the operation of the system as a whole it should be pointed out that the trackway apparatus herein disclosed is suitable for co-operation with train-carried governing means in the following manner: 55 When the train is on a portion of track which is supplied with track circuit current and local current of normal relative polarity, the governing mechanism allows the train to proceed at any rate not in excess of a high 60 speed such as 65 miles per hour; if the train occupies a stretch of track which is supplied with track circuit current and local current, the relative polarity of either of which currents is reversed, the governing mechanism 65 prevents the train from proceeding at speeds

in excess of an intermediate speed, such as 35 miles per hour; and if the train enters a stretch of track to which the supply of either local or track circuit current is for any reason discontinued, the governing mechanism 70 imposes a low speed limitation upon the train whereby the train is prevented from exceeding some low speed as 15 miles per hour.

In at least one form of train governing 75 apparatus suggested for this purpose the governing mechanism is controlled by the current or currents in the track rails through the medium of receiving appliances carried on the front of the locomotive. It is evident 80 that with apparatus of this character the source of track circuit current must at all times be connected with the rails in advance of the train or the wheels and axles of the train will shunt the track circuit current 85 away from the receiving apparatus and impose the low speed limitation. The track transformers are so arranged, as will be seen hereinafter, that all track circuits are fed by transformers connected in advance of a train, 90 irrespective of the direction of traffic.

As shown in the drawing, the parts all occupy the positions corresponding to normal condition, that is, the entire stretch of track is unoccupied and each signal S displays a 95 stop indication. I will now assume that a train moving from right to left enters the stretch of track shown in the drawing. The presence of this train in the portion of track to the right of E has de-energized W^9 so that 100 when the train enters the section immediately to the right of E, thus de-energizing the track relays R^9 associated with this section, the closing of back contact 71 does not energize relay G^9 but does energize relays G^2 105 and G^0 . Relay G^7 is not energized because its circuit is opened by the de-energization of relay W^7 which resulted from the opening of the front contacts of relay R^9 . The front contacts of relays G^2 and G^0 now close the 110 circuits for lamps 6 of signals S^2 and S^0 , which signals therefore display proceed indications to the train.

As the train enters section D—E the closing of a back contact of relay R^9 completes 115 the circuit for relay K^0 which thereupon becomes energized. The circuit is then complete for relay P^7 , since relay R^7 is also de-energized, and relay P^7 therefore picks up. The train is now supplied with track circuit 120 current from transformer T^7 , transformer T^0 is de-energized, and the shunt path around impedance 117 at relay R^9 is closed. Local current of normal relative polarity is supplied to the rails of the section from 125 transformer N^D over the front contacts of relay G^2 . The train is therefore allowed to move at high speed through section D—E.

If section C—D is occupied by another train, however, relay W^2 will be de-ener- 130

gized, relay G^2 will accordingly be de-energized, and signal S^2 will display a stop signal. This has no effect upon the supply of track circuit current to section D-E, but 5 local current of reverse relative polarity now supplied to this section between impedances 134 and 133 and no local current is supplied to the section between impedances 132 and 134. It follows therefore that the train entering section D-E at E can proceed at 10 speeds below 35 miles per hour as far as impedance 134 where its speed is further reduced to 15 miles per hour.

If section C-D is unoccupied but section 15 B-C is occupied, the consequent de-energization of relay W^4 reverses the polarity of the current supplied to relay W^2 which thereupon closes its reverse contacts, thus causing lamp 5 of signal S^2 to be energized 20 and the signal to display a caution indication. The local circuits for section D-E however are the same as when the track in advance is unoccupied as described above.

I will now assume that the track to the 25 left of point D is unoccupied, and that a train proceeds from section D-E into section C-D. Signal S^2 immediately displays a stop indication due to the de-energization of track relays R^2 and R^5 , whose front contacts control the circuit for relay W^2 . The entrance of the train into the section does not affect the track transformers, the track circuit current still being supplied from 30 transformers T^6 . Local current of normal 35 relative polarity is also supplied to the rails of the section throughout their length from local transformer N^c over front contacts of relay W^4 associated with the section B-C. The train is therefore permitted 40 to pass through section C-D at high speed. If section B-C is occupied, relay W^4 is de-energized so that its back contact is closed, and this causes the local current between impedances 134 and 133 in section 45 C-D to be reversed thus imposing an intermediate speed limitation through this portion of track, and causes the local current to be completely discontinued between the impedances 132 and 134, thus imposing a low 50 speed limitation upon the train through this portion of track.

It should also be pointed out that the entrance of the train into section C-D causes the de-energization of the opposing line 55 relay W^5 . Since relay K^5 is de-energized, the opening of front contact 17 of relay W^5 de-energizes relay W^3 . The opening of front contact 168 of relay W^3 opens, in turn, the circuit for relay W' which thereupon becomes 60 de-energized. A train moving from left to right through the section to the left of A cannot pick up relay G' and therefore cannot clear signal S' , which feature prevents the possibility of a head-on collision 65 between points A and D. It is obvious from

the drawing that similar protection is afforded for traffic in the opposite direction, should a train moving from left to right pass point A when the portion of track between points A and D is occupied.

As the train moving from right to left enters section A-B at point B, the two track relays R' and R^6 will become de-energized. The closing of the back contacts of relay R' connects primary 8 of transformer T^7 with a source of energy and track circuit current is therefore supplied to the rails of the section by this transformer. The closing of the back contacts of relay R^6 energizes relay K^6 which in turn picks up relay P' . At the same time, the opening of a front contact of track relay R^6 de-energizes relay W^6 which opens its front contacts and closes its back contacts. A front contact of relay K^6 , which relay is now energized, 85 closes a shunt around impedance 117 normally in series with winding 15 of relay R^6 . Relay W' is de-energized, its circuit having been interrupted by the opening of a front contact of relay R' . Consequently, 90 the closing of back contact 71 of relay R' does not pick up relay G' but relay G^8 is picked up, as are also the similar relays located at the other end of the passing siding F but not shown in the drawing. The operation of these relays is, however, the same as that of the similar relays G at siding F^a and it is therefore apparent that the polarity of the current supplied to relay W^8 will be reversed and the armatures of this relay will swing to the right, closing the normal contacts controlled thereby. The circuit for lamp 6 of signal S^8 is now complete and the signal accordingly displays a proceed indication.

It should be borne in mind that the polarity of the current supplied to relay W^8 is controlled by a relay not shown in the drawing, in the same manner that the polarity of current supplied to relay W^6 is controlled by relay G^2 . It will therefore be clear that when the block to the left of point A is unoccupied, the entrance of the train moving from right to left into section A-B, by causing the pick-up of the "G" relays at siding F, will cause relay W^8 to be energized in the normal direction. If the section immediately to the left of point A is occupied, relay W^8 and also relay G^8 will be de-energized, whereas if an opposing train occupies a portion of the block to the left of point A more remote than the first section, that is, the section immediately to the left of A, relay W^8 is energized in the reverse direction. In this latter case signal S^8 is at caution and local current of reverse relative polarity is supplied to the rails of section A-B throughout their length from transformer N^A . A train moving through this section from right to left

is therefore held below 35 miles per hour. If relay W^s is energized in the normal direction, lamp 6 of signal S^s is energized, whereupon this signal displays a proceed 5 indication. Simultaneously, local current of normal relative polarity is supplied to the rails of the section A—B throughout their length. If the section to the left of A is occupied however, the consequent de-energization of relays W^s and G^s causes lamp 10 4 of signal S^s to be energized, thus displaying a stop indication, and causes local current of reverse relative polarity to be supplied to section A—B between imped- 15 ances 134 and 133; but no local current will be supplied to the rails of this section between impedances 132 and 134. A train moving through section A—B under these conditions will be allowed to proceed at 35 20 miles per hour as far as point 134 but will be enabled to proceed past that point only at speeds below 15 miles per hour.

I will now assume that a train moving from left to right enters section A—B and stops. As explained above all the opposing line relays W^s , W^4 and W^2 will be de-energized. If a train moving from right to left enters section C—D at point D it is immediately reduced to slow speed even though it 30 is supplied with track circuit current from transformer T^4 because the local circuit for this section is now broken at front contact 170 of auxiliary relay K^4 . If this train proceeds, at slow speed, through section 35 C—D and enters section B—C, relay K^4 is not energized because the pickup circuit for this relay is broken at front contact 91 of line relay W^4 which is still de-energized. Relay W^s is of course de-energized and 40 relay K^s cannot pickup. No local current is supplied to section B—C and the speed of the train is thus held to 15 miles per hour throughout the portion of track shown in the drawing. A following train is sub- 45 jected to the same speed restrictions for the same reasons, for under no conditions can local current be supplied to the section when the associated relay W is de-energized prior to the entrance into the section of a train 50 moving in the direction in which that relay governs.

If, however, the portion of track shown in the drawing is unoccupied and a train moving from right to left passes into section 55 B—C at point C, the de-energization of line relay W^4 and the energization of relay K^4 closes a local circuit for section C—D which allows normal operation of a following train, that is, a following train is reduced to 60 35 miles per hour at point D, and to 15 miles per hour at impedance 134 in section C—D.

The operation of the apparatus as a train proceeds from left to right through the portion of track shown in the drawing will be 65 readily understood from the foregoing de-

scription of the operation of the apparatus when a train moves through the stretch from right to left.

It should be particularly noted that a points B and C the circuits for the auxiliary 70 relays K are such that they will not be picked up unless the opposing line relay W is in the proper position, that is, de-energized. This is of importance since it prevents energization of the relays K should 75 the associated line relay stick in its energized position.

Although I have herein shown and de- 80 scribed only one form and arrangement of railway traffic controlling apparatus embodying my invention, it is understood that various changes and modifications may be made therein within the scope of the appended claims without departing from the spirit and scope of my invention. 85

Having thus described my invention, what I claim is:

1. Railway traffic controlling apparatus comprising a section of railway track, a track relay for said section, a line relay 90 for said section controlled in part by the associated track relay, an auxiliary relay controlled in part by said track and line relays and in part by traffic conditions beyond said section, and a signal for said section controlled by the associated line relay 95 and auxiliary relay.

2. Railway traffic controlling apparatus comprising two sections of railway track, a track relay for each section, a line relay for 100 each section controlled in part by the associated track relay, a normally de-energized auxiliary relay associated with each line relay, and a circuit for each said auxiliary relay controlled by the associated line relay 105 and including in parallel two back contacts one on each said track relays.

3. In combination a portion of railway track comprising a forward, a middle and a rear section, a track relay for each end of 110 said middle section, a track relay for said forward section, a track relay for said rear section, a line relay associated with each track relay, a normally de-energized auxiliary relay associated with each line relay, 115 and means for simultaneously energizing two of said auxiliary relays when a train occupies the forward section and for simultaneously energizing the remaining auxiliary relays when a train occupies the rear 120 section.

4. In combination, a forward, a middle and a rear section of railway track, a track relay for each end of said middle section, a track relay for said forward section, a track relay for said rear section, a line relay associated with each track relay, a normally de-energized auxiliary relay associated with each line relay, means for connecting one terminal of each of the said 125

auxiliary relays to a common point, four back contacts one on each said track relay interposed in parallel between said common point and one terminal of an energy source and means controlled by the associated line relay for connecting the other terminal of each auxiliary relay with the remaining terminal of said source.

5. In combination a portion of railway track comprising a forward, a middle and a rear section, a track relay for each end of said middle section, a track relay for said forward section, a track relay for said rear section, a line relay associated with each track relay, a normally de-energized auxiliary relay associated with each line relay, means for simultaneously energizing two of said auxiliary relays when a train occupies said forward section and for simultaneously energizing the remaining auxiliary relay when a train occupies said rear section, and signals controlled by said auxiliary relay.

25 6. In combination, a forward, a middle and a rear section of railway track, a track relay for each end of said middle section, a track relay for said forward section, a track relay for said rear section, a line relay associated with each track relay, a normally de-energized auxiliary relay associated with each line relay, and a circuit for each said auxiliary relay including a source of energy, a back contact on each track relay and a contact on the associated line relay.

25 7. In combination, a forward, a middle
and a rear section of railway track, a track
relay for each end of said middle section,
a track relay for said forward section, a
track relay for said rear section, a line re-
40 lay associated with each track relay, a nor-
mally de-energized auxiliary relay associat-
ed with each line relay, and a circuit for
each said auxiliary relay including a source
45 of energy, a back contact on each track re-
lay, and a normal and a reverse contact on
the associated line relay connected in par-
allel.

8. In combination, a first and a second section of railway track, a line relay for said first section, a stick relay controlled in part by said line relay, and a local train controlling circuit for said second section including a contact on said line relay, a contact on said stick relay, and the rails of said second section between one end and an intermediate portion of such section.

portion of said section.

9. In combination, a first and a second section of railway track, a line relay responsive to traffic conditions in said first section, a stick relay controlled in part by said line relay, and a local circuit comprising a source of energy, a back contact of said line relay, a front contact of said stick relay, and the rails of a portion of said second section.

10. In combination, three successive sections of railway track, a line relay for the first section responsive to reversals of relative polarity of current, means controlled by traffic conditions in advance of the first section for supplying said line relay with current of one relative polarity or the other, a normally de-energized repeater relay for the first section, means controlled by a train in the third section for energizing said repeater relay if said line relay is energized in either direction, a line relay for the second section responsive to reversals of relative polarity of current, means for supplying said second line relay with current of one relative polarity or the other according as said repeater relay is energized or de-energized, track relays for the first and second sections for controlling said first and second line relays, and signals for the first and second sections controlled by said first and second line relays respectively.

11. In combination, three successive sections of railway track, a line relay for the first section responsive to reversals of relative polarity of current, means controlled by traffic conditions in advance of the first section for supplying said line relay with current of one relative polarity or the other, a normally de-energized repeater relay for the first section, means controlled by a train in the third section for energizing said repeater relay if said line relay is energized in either direction, a line relay for the second section responsive to reversals of relative polarity of current, means for supplying said second line relay with current of one relative polarity or the other according as said repeater relay is energized or de-energized, track relays for the first and second sections for controlling said first and second line relays, a second repeater relay for said second line relay, means controlled by a train in said third section for energizing said second repeater relay if said second line relay is energized in either direction, a signal for the first section controlled by said first line relay and said first repeater relay, and a signal for said second section controlled by said second line relay and said second repeater relay.

12. In combination, a stretch of railway track, means for at times supplying train controlling current to the rails of said stretch in accordance with traffic conditions, which current flows through the two rails of the stretch in multiple, and means for discontinuing such supply when the stretch is simultaneously occupied by two trains moving in opposite directions. 120 125

13. In combination, a stretch of railway track, a track circuit for said stretch, means effective when a train enters such stretch to supply local train controlling current to the rails of the section in multiple, provid- 130

ed the stretch is not occupied by an opposing train.

14. In combination, a stretch of railway track, means for supplying said stretch with local train controlling current when the stretch is occupied by trains moving in the same directions, which current flows through

the two rails of the stretch in multiple, and means for rendering said first means ineffective when the stretch is occupied by trains 10 moving in opposite directions.

In testimony whereof I affix my signature.

HERBERT A. WALLACE.
